UNITED STATES PATENT OFFICE

156,720

NASAL INHALATOR

Mack R. Fields, Libertyville, Ill., assignor to Abbott Laboratories, North Chicago, Ill., a corporation of Illinois

Original application April 30, 1948, Serial No. D. 146,072. Divided and this application September 28, 1949, Serial No. D. 5,196

Term of patent 14 years

(Cl. D83—1)

To all whom it may concern:

Be it known that I, Mack R. Fields, a citizen of the United States, residing in Libertyville, in the county of Lake and State of Illinois, have invented a new, original, and ornamental Design for a Nasal Inhalator, of which the following is a specification, reference being had to the accompanying drawing, forming a part thereof. This is a division of design application Serial No. D. 146,072, filed April 30, 1948.

In the accompanying drawing:

Figure 1 is a perspective view of a nasal inhalator embodying my new design;

Figure 2 is a plan view of the same device;

Figure 3 is a side elevation of the same device; and

Figure 4 is a rear elevation of the same device.
I claim:

The ornamental design for a nasal inhalator, substantially as shown.

MACK R. FIELDS.
